DESIGN FOR A BOTTLE

Albert C. Meyer, Glenshaw, Pa., assignor to Glenshaw Glass Company, Glenshaw, Pa., a corporation of Pennsylvania

Application August 1, 1934, Serial No. 52,764

Term of patent 7 years

To all whom it may concern:

Be it known that I, ALBERT C. MEYER, a citizen of the United States, residing at Glenshaw, in the county of Allegheny and State of Pennsylvania, have invented a new, original, and ornamental Design for a Bottle, of which the following is a specification, reference being had to the accompanying drawing, forming part thereof, in which Figures 1 and 2 are front and side elevational views, respectively, showing my new design. Opposite sides of the bottle are identical in appearance.

I claim:

The ornamental design for a bottle as shown and described.

ALBERT C. MEYER.
